UNITED STATES PATENT OFFICE.

FRANK W. SMITH, OF GARDNER, MASSACHUSETTS.

DESIGN FOR A SPOON.

SPECIFICATION forming part of Design No. 24,660, dated September 10, 1895.

Application filed April 27, 1895. Serial No. 547,422. Term of patent 3½ years.

To all whom it may concern:

Be it known that I, FRANK W. SMITH, of Gardner, in the county of Worcester and State of Massachusetts, have invented a new and original Design for a Handle for Spoons, Forks, and the Like, of which the following is a specification, reference being had to the accompanying drawings, showing a part thereof.

Figure 1 is a plan view of a spoon, showing my design, the said design being applicable to a fork or the like, as indicated by the dotted lines. Fig. 2 is an edge view of the spoon shown in Fig. 1.

The leading feature of the design is a fiddle-shaped handle having a marginal beading along its side margins and a shell at its butt-end.

In the drawings, a is a handle, a' the mar-

ginal beadwork near the two sides of the handle, and a^2 the shell which forms the butt-end 20 of the handle, the beadwork a' terminating at the opposite sides of the shell and the shell having a portion a^3 which projects at the extreme butt-end of the handle.

What I claim is—

The herein described design for the handle of a spoon, fork or other similar article, substantially as shown and described.

In testimony whereof I have signed my name to this specification, in the presence of 30 two subscribing witnesses, on this 19th day of April, A. D. 1895.

FRANK W. SMITH.

Witnesses:

G. F. BLAKE,
SETH HEYWOOD.
